LOW PROFILE HIGH-VOLTAGE, TRUCK-MOUNTED CIRCUIT BREAKER WITH STAGGERED TERMINALS, OR THE LIKE

Philip C. Netzel, Milmont Park, Pa., assignor to I-T-E Imperial Corporation, Philadelphia, Pa.

Filed June 26, 1972, Ser. No. 266,484

Term of patent 14 years

Int. Cl. D13—03

U.S. Cl. D26—13 R

FIG. 1 is a slightly elevated perspective view of a low profile high-voltage, truck-mounted circuit breaker with staggered terminals or the like.

FIG. 2 is a front elevational view.

FIG. 3 is a rear elevational view.

FIG. 4 is a top plan view.

FIG. 5 is a side elevational view.

I claim:

The ornamental design for a low profile high-voltage, truck-mounted circuit breaker with staggered terminals, or the like, as shown.
